UNITED STATES PATENT OFFICE.

WILLIAM C. NORTH, OF CLEVELAND, OHIO.

BROILER.

SPECIFICATION forming part of Letters Patent No. 366,679, dated July 19, 1887.

Application filed December 8, 1886. Serial No. 221,012. (No model.)

To all whom it may concern:

Be it known that I, WILLIAM C. NORTH, of Cleveland, in the county of Cuyahoga and State of Ohio, have invented certain new and 5 useful Improvements in Broilers, of which the following is a specification.

This invention relates to improvements in broilers; and it consists of a broiler-plate having a convex upper surface, a series of upward to projections thereon, a central opening, and a raised central disk over said opening, constructed and arranged substantially as herein-after described and claimed.

In the accompanying drawings, Figure 1 is 15 a perspective view of my new broiler. Fig. 2 is a vertical section of the same.

A is a plate or disk in concavo-convex form, in the center of which is an opening, B. On

the top surface of the plate are a series of raised lugs or ribs, C, and over the opening B is 20 placed a disk, D, supported on lugs d d, secured by means of a screw or bolt. The plate A is provided with a border-trough, E.

Having thus described my invention, what I claim, and desire to secure by Letters Patent, 25 is—

A broiler-plate having a convex upper surface, a series of upward projections thereon, a central opening, and a raised central disk over said opening, allowing the heated currents to pass laterally under the article being cooked, substantially as described.

WILLIAM C. NORTH.
